United States Patent Office

Des. 194,220
Patented Dec. 11, 1962

194,220

LATHE

Robert E. Diener, Shaker Heights, Ohio, assignor to The Warner & Swasey Company, Cleveland, Ohio, a corporation of Ohio

Filed Nov. 2, 1960, Ser. No. 62,710

Term of patent 14 years

(Cl. D54—6)

Des. 194,220

PAGE 2

FIG. 2

Des. 194,220

PAGE 3

FIG. 3

FIG. 4

FIG. 1 is a front perspective view of a lathe showing my new design, those portions obscured by the details shown in broken lines being the same in appearance as the corresponding portions shown in FIG. 3;

FIG. 2 is a rear perspective view thereof;

FIG. 3 is a front perspective view of a modified form of the lathe shown in FIGS. 1 and 2;

FIG. 4 is a rear perspective view thereof.

The broken-line portions in FIG. 1 are for illustrative purposes only.

I claim:

The ornamental design for a lathe substantially as shown and described.
